UNITED STATES PATENT OFFICE.

SAMUEL M. VAUCLAIN, OF ROSEMONT, PENNSYLVANIA, ASSIGNOR TO THE BALDWIN LOCOMOTIVE WORKS, OF PHILADELPHIA, PENNSYLVANIA, A CORPORATION OF PENNSYLVANIA.

TRIPLE-EXPANSION MALLETT LOCOMOTIVE.

Application filed November 25, 1925. Serial No. 71,407.

One object of my invention is to construct a triple expansion locomotive of the Mallet type, in which the boiler is rigidly secured to the frame on which are mounted the intermediate cylinders and the high pressure cylinders.

In the accompanying drawings:

Fig. 1 is a side view of a Mallet triple expansion locomotive illustrating my invention; and

Fig. 2 is an enlarged view showing the articulated joint between the two frames of the locomotive.

Referring to Fig. 1 of the drawing, 1 is the boiler, which is rigidly secured to the frame 2 of the locomotive. This frame 2 also carries the intermediate cylinders 3 and the high-pressure cylinders 4. The saddles 3^a and 4^a of these cylinders are rigidly secured to the boiler. The boiler is also supported by waist plates 5—5 and the rear structure 6 under the cab.

The forward end of the boiler overhangs the forward frame 7, which is connected to the frame 2 by an articulated joint 8 of ordinary construction. This forward frame carries the low-pressure cylinders 17. Bearing-blocks 9 on the boiler are arranged to slide on the supporting structure 10 on the forward frame 7.

On each frame are boxes for the axles 11, 11^a and 11^b, on which are mounted the driving-wheels 12, 12^a and 12^b. These wheels of each frame are connected together and to the piston-rods in the ordinary manner. This construction is omitted to avoid confusion.

High-pressure steam is taken from the steam space of the boiler through the pipes 13 and 13^a within the boiler and smoke-box, and through a pipe 13^b extending outside of the boiler to a pipe 13^c connected to the high-pressure cylinders 4.

The exhaust steam from the high-pressure cylinders 4 passes through a pipe 14 to the inlet passages of the valve-chests of the intermediate cylinders 3.

The exhaust from the intermediate cyl-

inders 3 passes through a pipe 15 which is connected to the exhaust pipes of the cylinders 3 by means of a ball-joint. The pipe 15 extends to and communicates with a pipe 16 which leads to the steam inlet ports of the valve-chests of the low-pressure cylinders 17 on the forward frame 7. The exhaust passages of the cylinders 17 are coupled to the nozzle 18 through a pipe 19, having a telescopic section which accommodates itself to the movement of the frame 7 in respect to the boiler.

While I have shown in Fig. 1 each frame having two driving-wheels at each side coupled to the piston of the respective cylinders, the number of driving-wheels may be varied, according to the type of locomotive to which my invention is applied. By the above construction, I have been able to provide a comparatively compact triple expansion locomotive of the Mallet type, in which the high-pressure cylinders and the intermediate cylinders are mounted on the frame which supports the boiler, and the low-pressure cylinders are on the forward frame.

I claim:

The combination in a triple expansion locomotive of the Mallet type, of a frame; a boiler to which the frame is rigidly secured; a forward frame connected by an articulated joint with the frame that supports the boiler, said boiler overhanging the said forward frame; low-pressure cylinders mounted on the forward frame; intermediate cylinders mounted on the forward end of the frame that supports the boiler and high-pressure cylinders mounted at the rear of the intermediate cylinders on the frame that supports the boiler; pipe connections between the boiler and the high-pressure cylinders, between the high-pressure cylinders and the intermediate cylinders, and between the intermediate cylinders and the low-pressure cylinders; and an exhaust pipe connecting the low-pressure cylinders with a nozzle in the smoke-box of the boiler.

SAMUEL M. VAUCLAIN.
